UNITED STATES PATENT OFFICE.

SIMEON BROWN AND THOMAS P. BROWN, OF PURITY, OHIO.

DESIGN FOR A WASHING-MACHINE PLUNGER.

SPECIFICATION forming part of Design No. 28,658, dated May 17, 1898.

Application filed March 9, 1898. Serial No. 673,271. Term of patent 14 years.

To all whom it may concern:

Be it known that we, SIMEON BROWN and THOMAS P. BROWN, citizens of the United States, residing at Purity, in the county of 5 Licking and State of Ohio, have invented and produced a new and useful Design for Washing-Machine Plungers, of which the following is a specification, reference being had to the accompanying drawings, forming a part 10 thereof.

In the drawings, Figure 1 is a perspective view illustrating the invention. Fig. 2 is a section on the line $\alpha\alpha$ of Fig. 1.

The leading or material feature of our design is the formation on a block 1 of rearwardly-extending parallel fingers 2 2, located, respectively, at equal distances from the ends of said block, and a finger 3, leading rearwardly from one end of said block, the upper 15 surface thereof being cut upon a compound

curve, as clearly shown. The lower surfaces of the fingers 2 2 and 3 are flat and lie in line with one another and with the bottom of the block 1. The forward end of the block 1 is formed with a series of vertically-disposed 25 ribs 4 4, having projecting fingers 5 at the lower ends thereof, and the under surface of the block 1 is formed with parallel grooves 6 6.

Having now described our invention, what we claim as new, and desire to secure by Letters Patent, is—

The design for a washing-machine plunger, substantially as herein shown and described.

In testimony whereof we affix our signatures in the presence of two witnesses.

SIMEON BROWN.
THOMAS P. BROWN.
